UNITED STATES PATENT OFFICE.

AUGUST DEAN, OF MERIDIAN, MISSISSIPPI, ASSIGNOR OF ONE-HALF TO CHARLEY H. DABBS, OF MERIDIAN, MISSISSIPPI.

BENDING MACHINE.

1,129,650.

Specification of Letters Patent. Patented Feb. 23, 1915.

Application filed May 18, 1914. Serial No. 838,802.

To all whom it may concern:

Be it known that I, AUGUST DEAN, a citizen of the United States, residing at Meridian, in the county of Lauderdale and State of Mississippi, have invented certain new and useful Improvements in Bending Machines, of which the following is a specification.

An object of this invention is the provision of a bending machine specially designed for straightening or re-shaping such parts of motor vehicles as the axle, controlling rod and the beams of the frame.

Another object is the provision of a device of this character embodying a frame on which the operating screws are slideable longitudinally and provided with means for locking the screws in adjusted position.

Another object is the provision of a novel type of clamp detachably connected with the end of each operating screw and adapted to secure the machine in operative position upon the object to be bent.

With these and other objects in view, the invention consists in the novel construction, arrangement and combination of parts as will be hereinafter specifically described, claimed and illustrated in the accompanying drawings, in which,

Figure 1 represents a side elevation of the machine applied to use, Fig. 2 represents a top plan view thereof, partly in section, Fig. 3 represents a transverse sectional view through the machine, partly broken away, and, Fig. 4 represents a detail sectional view, partly broken away, of one of the clamp retaining heads.

Referring to the drawing in detail, wherein similar reference numerals designate corresponding parts throughout the several views, the numerals 5 indicate a pair of side rails connected at their extremities by transverse beams 6 and constituting the frame of the bending machine. A plurality of rectilinear hollow housings 7 are provided adjacent the opposite ends with transverse openings slidably receiving the side rails 5 of the frame and having a threaded opening in one end wall of each housing to receive a set screw 8 whereby the housings are secured in adjusted position on the frame. Each of the housings 7 is formed with circular openings disposed at right angles to the openings receiving the side rails 5 and rotatably receiving a screw 9 having suit-

able apertures 10 in one end to receive an operating handle 11.

The frame carries three housings 7 and a corresponding number of operating screws 9, and the ends of the screws opposite the openings 10 are provided with a pair of spaced annular flanges or abutments 12 and 13. Heads consisting of two parts 14 and 15 having longitudinal extensions 16 are detachably secured together by bolts or the like 17 and the adjacent faces of the members 14 and 15 are provided with semi-circular openings or recesses rotatably receiving the said unthreaded portion of the screw 9 intermediate the collars 12 and 13. The heads are provided with transverse recesses through the walls of which pivot pins 18 are secured.

Within each of the housings 7 a block 19 having a central threaded recess receiving the screw 9 is located. The inner ends of a pair of clamping jaws 20 are pivotally secured on the ends of the pins 18 of each head and said jaws are provided intermediate their length with openings receiving a bolt 21 having a suitable nut 22 whereby the jaws may be drawn into clamping engagement with an object to be bent. The adjacent faces of the free extremities of the jaws 20 are provided with a plurality of recesses 23 of suitable shape to engage about the object to be bent.

In operation, when it is desired to straighten an axle of the usual I-beam type, as illustrated at 24 in Fig. 3, the jaws 20 of each pair are arranged to receive the horizontal portion of the axle 24 in the recesses 23 and the nuts 22 operated to rigidly clamp the jaws in operative position. The center or end screws 9 are operated by the handles 11 until the object is straightened or assumes the proper curvature. By separating the members 14 and 15 of the center head, it is clearly apparent that the ends of the operating screw 9 may be engaged against an axle spindle and the outer pairs of clamping jaws 20 engaged with the spokes of a wheel to remove the latter, or to straighten it, as desired.

What I claim is:

1. A device of the character described comprising a frame including longitudinal side rails, a plurality of housings slideable longitudinally on said frame, blocks positioned within said housings between said

105

110

side rails and having screw threaded openings therethrough, operating screws positioned through said threaded openings, means for securing said housings in adjusted position, and clamping jaws pivotally connected with the ends of said screws.

2. A device of the character described comprising a frame including longitudinal side rails, hollow housings adjustable longitudinally on said side rails, means for securing said housings in adjusted position, blocks positioned within said housings and having screw threaded openings there-

through, operating screws positioned through said threaded openings, two-part heads detachably secured to one end of said screws, jaws pivotally secured to said heads and having a plurality of recesses in their free extremities, and means for securing said jaws in operative position on an object. 20

In testimony whereof I affix my signature in presence of two witnesses.

AUGUST DEAN.

Witnesses:

A. K. TEAGUE,
J. R. HAWKINS.
